ELECTRONIC TUBE

William W. Eitel, San Bruno, and Jack A. McCullough, Millbrae, Calif., assignors to Eitel-McCullough, Inc., San Bruno, Calif., a corporation of California

Application October 2, 1942, Serial No. 460,722

10 Claims. (Cl. 250—27.5)

Our invention relates to an electronic tube, and more particularly to a type in which a plurality of electrode groups are enclosed within a single envelope.

It is among the objects of our invention to provide an improved arrangement of and mounting for the electrodes in the envelope.

Another object is to provide an improved support and lead arrangement for the grids.

The invention possesses other objects and features of advantage, some of which, with the foregoing, will be set forth in the following description of our invention. It is to be understood that we do not limit ourselves to this disclosure of species of our invention as we may adopt variant embodiments thereof within the scope of the claims.

Referring to the drawings:

Figure 1 is a perspective view of a tube embodying the improvements of our invention; and

Figure 2 is a vertical sectional view of the same.

In terms of broad inclusion, our improved tube comprises an envelope enclosing a plurality of groups of electrodes spaced about the longitudinal axis of the envelope, each group including an anode and grid and cathode. Conductor means for the anodes and grids extend through opposite ends of the envelope and a grid lead is sealed to the envelope portions intermediate the ends, the grids being unitarily supported on the single grid lead. The anodes are also preferably mounted on a common lead, and the cathode leads are preferably sealed to a stem on the envelope. We also preferably provide a shield in the envelope, interposed between the electrodes and the stem.

In greater detail, and referring to the drawings, our tube comprises an envelope of glass or the like having a cylindrical body with an enlarged upper portion 2 and a reduced lower portion 3. The latter portion is joined to a neck 4 at a shoulder 6, which neck carries a reentrant stem 7. The tube is fitted with a suitable base 8 having prongs 9.

Within the envelope are arranged a plurality of groups of electrodes, say four triode units, each including a filamentary cathode 11, grid 12 and anode 13. The electrodes in each group are coaxial; the respective axes of the groups being equally spaced about the longitudinal axis of the envelope. Anodes or plates 13 are tubular electrodes, preferably open at both ends, and carry heat radiating fins 14. The anodes are preferably unitarily supported by a bracket 16 on a common anode lead 17 disposed axially of the envelope and extending through the upper end 55

of the latter at seal 18. Cathodes 11 each have a pair of leads 19, all sealed to stem 7; these leads being connected to prongs 9 so that two of the filaments are connected in parallel to a pair of the prongs and the other two filaments in parallel to the other two prongs.

In our improved tube the grids 12 are unitarily supported on a common grid lead having an upturned portion 21 located axially of the envelope 10, and having a laterally extending portion 22 disposed transversely of the axis. Lead portion 22 preferably slopes downwardly and is sealed to the side portions of the envelope at seal 23 on shoulder 6. A terminal button 24 is provided on the 15 external end of the grid lead.

The grids are supported on the upper end of lead portion 21 by suitable means, as by spider arms 26 radiating from the lead and secured to grid terminal rings 27 by straps 28.

In order to protect stem 7 against heat and electron bombardment a circular metallic shield 29 is arranged transversely of the envelope between the electrodes and the stem. This shield is supported on the grid lead by welded joint 30. Apertures 31 in the shield provide free passage 25 for the cathode leads. To give full protection to the lower portions of the envelope, shield 29 is substantially co-extensive with the cross-sectional area of the envelope, the shield being preferably cup-shaped with a flange 32 extending upwardly alongside the inner surface of the glass wall. In a tube of the particular type illustrated the envelope sections are fused together at seal 33 in reduced portion 3. Our shield 29 thus also 30 protects this seal from heat originating at the electrodes.

We claim:

1. An electronic tube comprising an envelope having a stem, a plurality of anodes and associated grids and cathodes in the envelope, an anode lead sealed to the envelope, means unitarily supporting the anodes on said lead, a grid lead sealed to the envelope at a point spaced from said stem, means unitarily supporting the grids on said grid lead, and leads for the cathodes sealed to said stem.

2. An electronic tube comprising an envelope, a plurality of anodes and associated grids and cathodes in the envelope, conductor means for the anodes and cathodes sealed to the envelope, a grid lead sealed to the envelope intermediate its ends, and means unitarily supporting the grids on said grid lead, said grid lead extending inwardly from the side wall of the envelope and terminating adjacent the grids.

3. An electronic tube comprising an envelope having a stem at one end thereof, a plurality of anodes and associated grids and cathodes in the envelope, conductor means for the anodes sealed to the end of the envelope opposite said stem, a grid lead sealed to the envelope portions intermediate the ends thereof, means unitarily supporting the grids on the grid lead, and leads for the cathodes sealed to the stem, said grid lead extending inwardly from the side wall of the envelope and terminating at a point above said stem. 10

4. An electronic tube comprising an envelope, a plurality of anodes and associated grids and cathodes spaced about a longitudinal axis of the envelope, an anode lead extending longitudinally of said axis and sealed to an end of the envelope, means unitarily supporting the anodes on said lead, conductor means for the cathodes extending into the envelope, a grid lead angularly disposed to said axis and sealed to a side of the envelope, and means unitarily supporting the grids on said grid lead. 15

5. An electronic tube comprising an envelope, a plurality of anodes and associated grids spaced about a longitudinal axis of the envelope, an anode lead extending longitudinally of said axis and sealed to an end of the envelope, means unitarily supporting the anodes on said lead, a grid lead angularly disposed to said axis and sealed to a side of the envelope, means unitarily supporting the grids on said grid lead, said envelope having a stem at the end opposite the anode lead, cathodes associated with said anodes, and leads for the cathodes sealed to the stem. 20

6. An electronic tube comprising an envelope, a plurality of grids and anodes and cathodes in the envelope, conductor means for the anodes and cathodes extending into the envelope, a single grid lead sealed to a side of the envelope, and mounting means extending from the inner end of the grid lead unitarily supporting the grids on said lead. 25

7. An electronic tube comprising an envelope having a stem thereon, a plurality of grids and associated cathodes and anodes in the envelope, conductor means for the anodes extending into the envelope, a grid lead sealed to the envelope, means unitarily supporting the grids on said lead, leads for the cathodes sealed to the stem, and means in the envelope for shielding the stem. 30

8. An electronic tube comprising an envelope, a plurality of groups of electrodes spaced about the longitudinal axis of the envelope, each group including an anode and grid and cathode, conductor means for the anodes and cathodes extending through opposite ends of the envelope, a grid lead having a section extending transversely of said axis and sealed to the envelope portions intermediate said ends, and means unitarily supporting the grids on the grid lead. 35

9. An electronic tube comprising an envelope having a stem, a plurality of groups of electrodes in the envelope, each group including a grid and cathode and anode, leads for the cathodes sealed to the stem, conductor means for the anodes extending into the envelope, a grid lead sealed to the envelope, means unitarily supporting the grids on the grid lead, and a shield supported on the grid lead and interposed between the electrodes and said stem. 40

10. An electronic tube comprising an envelope having a stem, a plurality of groups of electrodes in the envelope, each group including a grid and cathode and anode, leads for the cathodes sealed to the stem, conductor means for the anodes extending into the envelope, a grid lead sealed to the envelope, means unitarily supporting the grids on the grid lead, and a shield supported on the grid lead and extending transversely of the envelope between the electrodes and said stem, said shield having a peripheral flange lying adjacent the side wall of the envelope. 45
